(57) CLAIM

The ornamental design for a luminaire, as shown and described.

DESCRIPTION

FIG. 1 is a perspective view of a luminaire, showing our new design;

FIG. 2 is a top view thereof;

FIG. 3 is a left view thereof; the right view being a mirror image thereof;

FIG. 4 is a front view thereof; and,

FIG. 5 is a bottom view thereof.
